chine Company, Columbus, Ohio, a corporation
of Ohio

Application August 4, 1940, Serial No. 351,302

14 Claims. (Cl. 94—46)

Our invention relates to apparatus for surfacing roads. It has to do, more particularly, with apparatus for producing a smooth and level surface on a layer of material which is being applied to an old road surface or to a rough graded surface. The invention is useful with various materials such as bituminous mixes, concrete, et cetera.

One of the objects of our invention is to provide apparatus for surfacing roads which is of such a nature that the irregularities of the surface being covered by the material will be averaged out in the finished surface so that the finished surface will be free of sharp irregularities or bumps.

Another object of our invention is to provide apparatus for surfacing roads which is of such a nature that it may be used in resurfacing old road surfaces to produce a surface having the same general grade as the old surface with the sharp irregularities thereof eliminated or to produce a surface having an entirely different grade from the surface being covered.

Another object of our invention is to provide an apparatus for surfacing a road which includes a finishing member adapted to smooth and level the surface of the material being applied, the apparatus being of such a nature that the finishing member resting on the layer of material will not support any substantial weight of the machine in order to prevent undue compaction of the layer of material so as not to retard the "curing" or "setting" of the material.

Another object of our invention is to provide apparatus of the type indicated which is very effective but which is relatively simple.

The apparatus which we preferably employ consists of two main units. These units are a material feeding unit and a material finishing and leveling unit. The material feeding unit may be of any suitable type and is carried by suitable traction means which operate upon the sub-grade or the old road surface being covered. The finishing unit is associated with the material feeding unit in such a manner that relative vertical movement between these two units is permitted as the apparatus moves along. The finishing unit embodies a transversely extending screed member which is disposed behind the material feeding unit. The material feeding unit serves to feed and deposit the material in front of the screed member on the surface being covered, and the screed member acts to level off the material and to smooth it.

It will be apparent that since the material

feeding unit operates on the rough sub-grade or old road surface, it will be moved vertically because of such irregularities. To reduce such movement, the unit is preferably carried by relatively long caterpillar traction elements. These substantially prevent small irregularities from affecting this unit. However, the larger and sharp irregularities in the surface being covered will still produce some vertical movement of this unit. This vertical movement of the material feeding unit has a tendency to move the screed of the finishing unit, which is pulled along behind the feeding unit, vertically and thereby cause the sharp irregularities of the surface being covered 10 to be reflected in the finished surface. We provide means connected with the finishing unit and with the feeding unit for automatically controlling the level of the screed member so as to average out the sudden rises and depressions of 15 the surface being covered as reflected in the finished surface. In other words, if the surface being covered has sharp rises and depressions, these will be reflected in the finished surface but will be gradual rises and depressions so as to be 20 almost unnoticeable. Consequently, the surface produced by our apparatus will be a very smooth riding surface.

The preferred embodiment of our invention is illustrated in the accompanying drawings wherein similar characters of reference designate corresponding parts and wherein:

Figure 1 is a perspective view of a machine embodying the principles of our invention.

Figure 2 is a side elevation of the machine.

Figure 3 is a rear view of the finishing unit showing the hydraulic means for controlling the elevation of the screed associated therewith.

Figure 4 is a diagrammatic view of our machine showing it in operation and illustrating how small 35 irregularities of the surface being covered have substantially no effect on the machine.

Figure 5 is a similar view illustrating how the machine functions when the material feeding unit starts to pass up over a sharp bump.

Figure 6 is a vertical sectional view taken 40 through one of the automatic control valves which is associated with the hydraulic mechanism that automatically controls the level of the screed.

Figure 7 is a similar view but taken at right angles to that of Figure 6.

Figure 8 is a vertical sectional view taken 45 through a check valve which is also associated with the hydraulic system that controls the level of the screed.

Figure 9 is a perspective view of the rear end of our machine illustrating how the means for controlling the level of the screed may cooperate with a form or predetermined grade line along one side of the surface being covered.

Figure 10 is a diagrammatic view illustrating how the screed level controlling means may cooperate with a curb disposed along the edge of the surface being covered.

With reference to the drawings, we have illustrated our machine as consisting mainly of a material receiving and feeding unit 1 and a material leveling and finishing unit 2. The unit 1 is adapted to receive the material, which preferably has been previously mixed, and to deposit it on the surface being covered in front of the unit 2. The unit 2 is adapted to level off and surface such material.

The unit 1 may be of any suitable type. The specific structure of this unit does not form a part of the present invention. It is merely necessary that it be of such a nature that it will receive the material and feed it to the unit 2. For example, it may be similar to the material receiving and spreading units disclosed in the patents to Mosel, Nos. 2,054,436 and 2,054,437, which issued September 15, 1936. Other types of feeding units may also be employed. For example, the hopper 3 of the unit 1 may be provided with a movable bottom 3a in the form of an endless conveyer which will serve to feed the material rearwardly and deposit it in front of the unit 2. The hopper 3 preferably receives the mixed material from a dump truck or other suitable source.

The unit 1 is carried by a pair of relatively long caterpillar traction units 4. These units 4 will pass over small irregularities of the sub-grade or old road surface without any appreciable vertical movement of the unit 1.

The unit 2 consists of a transversely extending screed member 5 and a U-shaped supporting frame 6 from which it is suspended. This U-shaped supporting frame 6 consists of forwardly extending draw plates 7 which extend along the opposite sides of the unit 1 and which have their forward ends pivotally connected thereto, as at 8. The pivot points 8 are located substantially midway between the front and rear ends of the unit 1 so that vertical movement of the unit 1 will have a minimum effect on the unit 2. The rear ends of the plates 7 are connected to the lower portions of upstanding screed supports and guides 9. These screed supports and guides 9 are rigidly joined together by means of a transversely extending beam 10. The screed 5 is suspended from the supports 9 in a manner to be explained later.

The entire weight of the unit 2 is carried by a pair of longitudinally extending runner members 11. Each of these runner members 11 is disposed directly inside the plate 7. These runner members are comparatively long and each of them is pivotally connected, as at 12, to the plate 7. The pivot point 12 is located substantially midway between the front and rear ends of the plate 7 and substantially midway between the front and rear ends of the runner 11. A pivot 12a carried at the front end of runner 11 operates in an arcuate slot 12b formed in the plate 7. Each plate 7 carries a vertically disposed plate 13 which is mounted thereon for vertical adjustment by means of the pin and slots 14. The plates 13 are provided at the ends of the screed unit 5 and are adapted to limit spread-

ing of the material beyond the ends of the screed member and to form straight edges on the layer of material produced by the machine.

The screed unit 5 consists of a beam 15. From the beam 15, there is suspended a screed member or finishing member 16. The member 16 may be suspended from the member 15 by means of the adjustable bolts 17. However, it is to be understood that we may employ any suitable type of screed unit. For example, we may use a screed unit of the type disclosed in the co-pending application of Millikin and Apel, executed on the 29th day of July, 1940. A rotatable screw spreading member 3b, or spreading member of any other suitable type, may be disposed in front of the screed unit to spread the material laterally before it is acted on by the screed. This screw may be carried by the unit 2 or the unit 1 and may be of a type disclosed in the said Mosel patents.

In order to suspend the screed unit 5 from the supports 9, we provide the following structure. This structure comprises a piston rod 19 which has its lower end secured to the end of the beam 15. The upper end of this rod 19 carries a piston 20 which is disposed in a vertically disposed hydraulic cylinder 21. The cylinder 21 is carried on the upper end of the support 9 between the spaced columns 9a and 9b thereof. The beam 15 of the screed unit has its ends disposed between the columns 9a and 9b of the supports 9 and these columns function as guides for guiding vertical movement of the screed unit. Each of the hydraulic cylinders 21 has a line 22 leading from the upper end thereof and a line 23 leading from the lower end thereof. The lines 22 and 23 are connected to an automatic control valve 24. The details of this valve 24 will be described later.

Two valves 24 are provided and they are located adjacent the ends of the screed unit 5. Each of these valves has its cylindrical housing immovably supported by a bracket 25 on the beam 15 of the screed unit. Each of the valves 24 has a rod or stem 26 projecting from the lower end thereof. This stem 26 is vertically movable relative to the housing of the valve. It has its lower end hingedly connected at 27 to the upper end of a sleeve 28. The lower end of the sleeve 28 is internally threaded and receives the threaded pin 29. This pin 29 has its lower end pivotally connected, as at 30, to a bracket 31. The bracket 31 is rigidly connected to the vertical portion 32 of a leveling arm 33. This arm extends forwardly over the screed unit 5 and then downwardly and forwardly to the point 34 where it is pivotally connected to the side of the unit 1. Suitable guides 35 may be provided on the unit 1 for preventing lateral movement of the arms 33 but for permitting vertical movement thereof. The points 34 are substantially in alignment with the points 8 where the units 1 and 2 are pivotally connected together. Furthermore, the points 34 are almost at the same level as the points 8 so that they will be close to the line of pull between the units 1 and 2.

The lower ends of the portions 32 of the arms 33 are turned rearwardly, as at 36. The extreme rear ends of these arms are pivotally connected as at 37, to the upper ends of the links 38. The links 38 carry collars 39 on their lower ends which are rotatively carried by a transversely extending shaft 40. This shaft 40 has collars 41 keyed thereon which are provided with depending portions 42 that are pivoted, as at 43, to brackets 44

which are secured to the upper surfaces of the pans 45. The pans 45 each embody a flat plate having an upstanding flange 46 formed thereon which extends around the periphery thereof. The pans 45 will rest on the finished layer of material and the flanges 46 will prevent them from digging into the material. Draw bars 47 have their forward ends pivotally connected to the screed unit, as at 48. The rear ends of these draw bars are integrally secured to the collars 39. A transverse shaft 49 has its ends connected to the bars 47 and is disposed parallel to the shaft 40. The shafts 40 and 49 serve to keep the draw bars 47 parallel with each other. A turnbuckle 50 is connected to each end of the shaft 49 and its lower end is pivotally connected to the pan 45, as at 51. By adjusting these turnbuckles, the pans 45 may be adjusted to the proper position relative to bars 47.

It is desirable to adjust the stems 26 of the valves 24 in and out of the valve housings in order to vary the elevation of the points 30. For this purpose, each of the valves 24 has a shaft 52 rotatably carried thereby. The lower end of this shaft 52 has a flanged gear 53 keyed thereon which meshes with a gear 54 keyed on the lower end of the stem 26. By rotating shaft 52, the sleeve 28 is rotated and causes the pin 29 to thread into or out of the sleeve. Consequently, this raises or lowers the point 30 and, changes the distance between the valve 24 and pan 45. Thus, by rotating the shafts 52, the elevation of the pans 45 relative to the screed member 16 can be adjusted.

The structure of each of the valves 24 is illustrated best in Figures 6 and 7. Each valve comprises a cylindrical housing having the stem 26 projecting from the lower end thereof, as previously explained. The valve stem 26 is slidably mounted in a packing gland 55 threaded into the lower end of the valve housing. This stem 26 carries axially spaced enlargements or collars 56, 57, 58 and 59 which fit tightly within the valve housing but which do not interfere with vertical movement of the stem within the housing. Thus, a middle annular chamber 60, an upper annular chamber 61 and a lower annular chamber 62 are produced around the valve stem. The valve housing is provided with an inlet port 63, which is always in communication with the chamber 60. The wall of the valve housing has a vertical passageway 64 formed therein which is provided with an upper opening 65 that always communicates with the chamber 61 and a lower opening 66 that always communicates with the chamber 62. The passage 64 is provided with an outlet opening 67 formed in the wall of the valve housing. The wall of the valve housing is also provided with an upper port 68 and a lower port 69 which are normally closed by the portions 58 and 57 of the valve stem.

As indicated best in Figure 3, the inlet ports 63 of the two valves 24 are connected together by a line 70. The outlet ports of the two valves are connected together by a line 71. The conduits 23 are connected to the ports 68 of the two valves and the conduits 22 are connected to the ports 69 of the two valves. The line 70 is connected by means of a high pressure line 72 to the discharge side of a hydraulic pump 73. The inlet side of the pump is connected by a line 74 to an oil tank 75. A line 76 connects the line 72 to the line 71. This line 76 has an adjustable automatic relief valve 77 incorporated therein. A connection is provided between the line 76 and

the line 72 and a variable pressure control valve 78 is incorporated therein. A low pressure line 79 is connected to the line 76 and leads to the bottom of the tank 75.

Each of the lines 23 has a check valve 80 incorporated therein. The structure of this check valve is illustrated in Figure 8. This check valve has an inlet passageway 81, the inner end of which is normally closed by a ball valve 82 held on its seat by a spring 83. The resistance of the spring may be varied to vary the pressure of incoming liquid necessary to unseat the ball 82. A by-pass passageway 84 extends around the ball check valve 82. This passageway includes a port 85 upon the upper end of which a ball 86 normally seats. The ball 86 is held on its seat by a spring 87 which may be adjusted to vary the force of the upward pressure of liquid through the port 85 required to unseat the ball 86 from its seat. The port 85 communicates with outlet passage 88. This valve 80 will function in a manner to be described later. The inlet 81 is connected to opening 68 in valve 24 by a portion of line 23.

In using our machine, the pans 45 are adapted normally to be disposed at the same level as the finishing member 16. In starting to lay the material, the pans 45 may be adjusted to the proper height by means of the shafts 52. For example, if it is desired to lay six inches of material, the pans 45 will be adjusted to a height six inches above the lower edges of the runners 11. The pans will preferably be disposed on the surface of a previously laid layer which the new layer, produced by our machine, is adapted to join, or planks or other suitable temporary supports of the proper thickness behind the machine. The screed unit 5 will then be raised automatically by the hydraulic means until the member 16 is at the same level as the pans 45. From an inspection of Figure 3, and Figures 6, 7 and 8, and from the following description, the manner in which this is accomplished will be clear. Since the member 16 is initially lower than the pans 45, the stems 26 of the valves 24 will be forced upwardly, because the leveling arms 34, exposing the openings 68 and 69. The oil pump 73 will force oil under pressure through line 72, line 70, through inlets 63 of the valves 24, through chambers 60, through the upper openings 68, through check valves 80 and conduits 23 into the lower ends of the screed hoisting cylinders 21. This will move the pistons 20 upwardly. Part of the oil in the upper ends of the cylinders 21 will be forced into the lines 22, through openings 69, through chambers 62, through openings 66 and passageways 64, through the line 71 and into the line 76, into the line 79 and then into the tank 75. The pump 73 will maintain, in the system, the pressure for which the relief valve 77 is set. When the screed unit is lifted to a height such that the member 16 is at the same level as the pans 45, the valve stem 26 will have been returned to its neutral position indicated in Figure 7 because the level of the pans 45 and the member 16 will coincide at this time. This is accomplished because when the screed unit 5 is lifted, the housings of the valves 24 are moved upwardly relative to the stems 26. When the member 16 is at the same level as the pans 45, the portions 57 and 58 of the stems will be in covering relationship to the openings 68 and 69. If the pans 45 are initially set at a lower level than the finishing member 16, the hydraulic system will func-

tion in a similar manner to lower the screed unit 5 until the pans 45 and the member 16 are at the same level.

The valves 80 are provided to prevent settling or gradual lowering of the screed unit 5. When the valve 24 is in proper condition to allow the oil to enter inlet 81 of valve 80, associated therewith, the ball 82 will be unseated. However, if the weight of the screed unit 5 starts to force the oil back through line 23 past the ball 82, the ball will be seated. Thus, settling of the screed will be precluded. However, the by-pass 84 is provided to permit the oil to flow from line 23 back past the ball valve 82 when desired. This is desirable when the valves 24 are in such position that oil will be supplied to the upper ends of cylinders 21 to force the pistons 20 downwardly. Then the pressure of the oil will be sufficient to unseat ball 86 and allow the oil to pass through by-pass 84. The spring 87 is set so that the weight of the screed alone is not sufficient to unseat the ball 86. To unseat the ball 86, there must also be positive pressure exerted on the upper ends of the pistons 20 by oil entering the upper ends of cylinders 21 which will produce an increased pressure in lines 23.

After the machine is adjusted and the laying of the material begins, it will function in the manner illustrated in Figures 4 and 5. The pans 45 and the member 16 will be at the same level. The pans 45 will be riding on the surface of the layer of material produced by the machine. As the machine moves along, the material is fed from the unit 1 and is deposited in front of the screed unit 5. Member 16 of the screed unit will level off this material to a predetermined height. As indicated in Figure 4, because of the long traction members 4, small irregularities in the surface being covered will be bridged thereby and will not cause any appreciable vertical movement of the unit 1. The thickness of the layer of the material is obtained as previously indicated by shortening or lengthening the distance between the valves 24 and the pans 45, which may be accomplished by rotating the shafts 52.

The screed member 16 will operate in the same plane as long as the line CD remains parallel with the line AB passing through the pivot point 34 where the leveling arm 33 is pivoted to the unit 1. The line CD corresponds to the lower surfaces of the pans 45 and the finishing member 16 of the screed. Line AB is the average contour of the base. As long as the lines AB and CD are parallel, the valves 24 will not function and the hydraulic system will merely serve to keep the screed unit at the predetermined level. As the machine moves along, the runners 11 will also bridge small irregularities so that they will not produce vertical movement of the unit 2. The runners serve to support all of the weight of the screed unit which is not supported by the unit 1. Thus the weight is kept off of the screed unit 5 so that it will not compress the layer of material to an undesirable extent.

As indicated in Figure 5, if the lines AB and CD become non-parallel, due to the unit 1, for example, passing up over a sharp rise in the surface being covered, the valves 24 will function to change the level of the screed unit. When the unit 1 tilts rearwardly and downwardly in the manner indicated in Figure 5, there is a tendency for the member 16 to be lifted. This would produce a sharp bump in the finished surface unless some means were provided to overcome it. The valves 24 will, however, act to

lower the screed member 16 automatically. Movement of the unit 1 relative to the unit 2 in the manner indicated will move the housings of the valves 24 upwardly relative to the stems 26 of the valves. This will uncover the openings 68 and 69, in the manner previously described, and will allow the oil to be displaced from the lower ends of the cylinders 21 to the upper ends thereof so as to lower the screed unit. When the line AB and the line CD are again in parallel relationship, the valves 24 will cease to function and the screed unit will, at this time, be in its original position and will be held in such position until the lines AB and CD are again out of parallel relationship. This leveling out process will be a gradual process, as the machine moves forward, and, therefore, will eliminate all sharp bumps and will produce a smooth riding surface. The extent of movement of the screed unit relative to the extent of the vertical movement of the unit 1 is governed by the ratio of the distance from the points 34 to the points 37 with the distance from the points 30 to the points 37. We have found that a suitable ratio is 12 to 1 although other ratios may also be used.

If the runners 11 ride over sharp irregularities and cause vertical movement of the unit 2, the valves 24 will function in a manner similar to that described in the preceding paragraph to change the level of the screed member. For example, if the member 16 is lifted, the housings of the valves 24 will be lifted relative to the stems 26. This will automatically lower the screed unit in the manner previously described. When the lines AB and CD are again in parallel relationship, the valves 24 will cease to function. This vertical movement of the screed unit, caused by the unit 1 moving vertically or the runners 11 moving vertically, will be compensated for and the sharp irregularities of the surface over which they operate will not be present in the finished surface but will be averaged out.

In Figure 9, we have illustrated how our machine may be employed with a form or other grade line set along the edge of the surface being covered. As indicated, we may provide a form or line E which is supported on stakes F and is set at a predetermined grade line. One of the pans 45 is eliminated, the shaft 40a is extended and carries a roller 45a, or other suitable member, which will roll on the form E. The other pan will operate on the finished layer as before. The machine will function exactly the same as before with the exception that a new grade line, corresponding to that of line E, will be produced on the finished layer at the side adjacent the form E regardless of the grade of the surface over which the machine passes. In some instances, it may be desirable to provide rollers 45a at both sides which cooperate with forms E. In such instances, a complete new grade corresponding to that of the forms E may be established. The unit 1 will pass over the irregularities of the sub-grade or old road surface, but the rollers 45a operating on the forms E will cause automatic adjustment of the screed to average out these irregularities.

In Figure 10, we show a roller 45a operating on a concrete curb G. The machine will lay the material next to the curb to a level corresponding to that of the curb, if desired. Thus, the machine may be used for joining effectively one layer of material to another layer disposed along the edge thereof.

It will be apparent from the above description

that we have provided apparatus for surfacing roads which is of such a nature that the irregularities of the surface being covered by the material will be averaged out in the finished surface so that the finished surface will be free of sharp irregularities or bumps. Our apparatus is of such a nature that it may be used in resurfacing an old road to produce a surface having the same general grade as the old surface with the sharp irregularities thereof eliminated or it may cooperate with a new grade line, set along the edge of the road, to produce a surface having an entirely different grade from the surface being covered. Furthermore, it will be apparent that the apparatus is of such a nature that the finishing member resting on the layer of material will not support any substantial weight of the machine. Consequently, the material will not be compressed to such an extent that it will be sealed and will retard "curing" or "setting" thereof. Our apparatus is very effective but is relatively simple.

Although we specify that the hydraulic system automatically controls the level of the screed unit, it is to be understood that it can be employed for controlling the level of any leveling or similar member provided on a road building machine.

Various other advantages will be apparent from the preceding description, the drawings and the following claims.

Having thus described our invention, what we claim is:

1. A machine for surfacing a road or the like comprising a unit embodying a screed member, a frame for supporting said screed member, a hydraulic cylinder and piston unit for suspending said screed member on said frame for vertical movement, means for supporting said frame for movement along the surface to be covered, automatic means for actuating said cylinder and piston unit to change the elevation of said screed on said frame to compensate for vertical movement of said frame as the machine moves along the surface to be covered, said means comprising a control member adapted to operate on the finished surface produced by the screed, said control member being connected to a control valve which serves to actuate said cylinder and piston unit whenever the frame moves vertically relative to said control member.

2. A machine according to claim 1 wherein the means for supporting said frame embodies longitudinally extending elongated runner members which slide along the surface to be covered and which are pivotally connected to said frame.

3. A machine for surfacing a road or the like comprising a unit embodying a screed member, a frame for supporting said screed member, a hydraulic cylinder and piston unit for suspending said screed member on said frame for vertical movement, means for supporting said frame for movement along the surface to be covered, automatic means for actuating said cylinder and piston unit to change the elevation of said screed on said frame to compensate for vertical movement of said frame as the machine moves along the surface to be covered, said means comprising a control member normally disposed at the same level as the finishing surface of the screed, said control member being connected to a control valve which serves to actuate said cylinder and piston unit to move the screed vertically relative to the frame to return it to the same level as the control member whenever the screed is moved vertically relative to the control member by ver-

tical movement of the supporting frame as the machine moves along.

4. A machine for surfacing a road comprising a leveling member adapted to act upon material applied to the surface to be covered, means for supporting said member on the machine for vertical movement, said means comprising a hydraulic cylinder and piston unit, means for supporting said machine for movement along the surface to be covered, said means operating on the surface to be covered, and means for automatically changing the vertical position of said leveling member on the machine in accordance with vertical movement of the machine as it moves along over the surface to be covered, said means comprising a control member supported on the machine for vertical movement relative to the leveling member and adapted to ride on a surface having a predetermined grade line, said control member being connected to a control valve which serves to actuate said cylinder and piston unit to move said leveling member vertically on the machine in an opposite direction whenever the leveling member moves vertically relative to the control member in one direction during movement of the machine along the surface to be covered.

5. A machine for surfacing a road comprising a material feeding unit, means for supporting said unit for movement along the surface to be covered, said means operating on the surface to be covered, a material-leveling unit embodying a leveling member disposed behind the first unit and adapted to level off material supplied by said unit, means for supporting said second unit for movement along the surface to be covered, said means operating on the surface to be covered, means for connecting said units together to permit relative vertical movement thereof, hydraulic cylinder and piston units for supporting said leveling member on the second unit, and means for automatically changing the vertical position of said leveling member as the machine moves vertically in passing along over the surface to be covered, said means comprising a control member supported on the machine for vertical movement relative to the leveling member and adapted to ride on a surface having a predetermined grade line, said control member being disposed at a point behind said leveling member and being connected to the rear end of a lever arm, said lever arm having its forward end pivotally connected to said first-named unit, a control valve for actuating said cylinder and piston units, said control valve being connected to said lever arm at a point intermediate the points of connection of said arm to said control member and to said first-named unit.

6. A machine for surfacing a road comprising a leveling member adapted to act upon material applied to the surface to be covered, means for supporting said member on the machine for vertical movement, said means comprising hydraulic cylinder and piston unit for suspending said leveling member on the machine, means for supporting said machine for movement along the surface to be covered, said means operating on the surface to be covered, and means for automatically changing the vertical position of said leveling member on the machine in accordance with vertical movement of the machine as it moves along over the surface to be covered, said means comprising a control member supported on the machine behind said leveling member for vertical movement relative thereto and adapted

to operate upon the surface produced by said leveling member, said control member being connected to a control valve which serves to actuate said cylinder and piston units to move said leveling member vertically on the machine in an opposite direction whenever the leveling member moves vertically relative to the control member in one direction during movement of the machine along the surface to be covered.

7. A machine for surfacing a road comprising a material feeding unit, means for supporting said unit for movement along the surface to be covered, said means operating on the surface to be covered, a material-leveling unit embodying a leveling member disposed behind the first unit and adapted to level off material supplied by said unit, means for supporting said second unit for movement along the surface to be covered, said means operating on the surface to be covered, means for connecting said units together to permit relative movement thereof, hydraulic cylinder and piston units for suspending said leveling member from the second unit, and means for automatically changing the vertical position of said leveling member as the machine moves vertically in passing along over the surface to be covered, said means comprising a control member supported on said second-named unit behind said leveling member for vertical movement relative thereto and adapted to operate upon the surface produced by said leveling member, said control member being connected to the rear end of a lever arm, said lever arm having its forward end pivotally connected to said first-named unit, a control valve for actuating said cylinder and piston units, said control valve being connected to said lever arm at a point intermediate the points of connection of said arm to said control member and to said first-named unit and being actuated by movement thereof.

8. A machine for surfacing a road comprising a leveling member adapted to act upon material applied to the surface to be covered, means for supporting said member on the machine for vertical movement, said means comprising hydraulic cylinder and piston units, means for supporting said machine for movement along the surface to be covered, said means operating on the surface to be covered, and means for automatically changing the vertical position of said leveling member on the machine in accordance with vertical movement of the machine as it moves along over the surface to be covered, said means comprising a control member supported on the machine for vertical movement relative to the leveling member at a point behind said leveling member and adapted to ride on a surface having a predetermined grade line, said control member being carried by the rear end of a lever arm, said lever arm having its forward end pivotally connected to the machine at a point in front of said leveling member, a control valve for actuating said cylinder and piston units, said control valve being connected to said lever arm at a point intermediate the points of connection of said arm to said control member and to said machine and being actuated by movement thereof.

9. A machine for surfacing a road comprising a leveling member adapted to act upon material applied to the surface to be covered, means for supporting said member on the machine for vertical movement, said means comprising a hydraulic cylinder and piston unit, means for supporting said machine for movement along the

- surface to be covered, said means operating on the surface to be covered, and means for automatically changing the vertical position of said leveling member on the machine in accordance with vertical movement of the machine as it moves along over the surface to be covered, said means comprising a control member supported on the machine behind said leveling member for vertical movement relative thereto and adapted to operate upon the surface produced by said leveling member, said control member being carried by the rear end of a lever arm, said lever arm having its forward end pivotally connected to the machine at a point in front of said leveling member, a valve for controlling said cylinder and piston unit, said control valve being connected to said lever arm at a point intermediate the point of connection of said arm to said control member and to said machine.
10. A machine for surfacing a road comprising a unit supported for movement along the surface to be covered by means operating on said surface, a material leveling unit embodying a leveling member adapted to act upon material applied to the surface to be covered, means for supporting said leveling member on the second-named unit and adapted to be actuated to move said leveling member to various vertical positions on said second-named unit, means for supporting said second-named unit for movement along the surface to be covered, said means operating along the surface to be covered, means for connecting said units together to permit relative vertical movement thereof, and means for actuating said leveling member supporting means to automatically change the vertical position of said leveling member as the machine moves vertically in passing along over the surface to be covered, said means comprising a control member supported on the machine for vertical movement relative to the leveling member at a point behind said leveling member and adapted to ride on a surface having a predetermined grade line, said control member being carried by the rear end of a lever arm, said lever arm having its forward end pivotally connected to said first-named unit, said lever arm being operatively connected to said leveling member supporting means at a point intermediate the ends of said arm so as to actuate said leveling member supporting means to move said leveling member vertically in an opposite direction whenever the leveling member moves vertically relative to the control member in one direction during movement of the machine along the surface to be covered.
11. A machine for surfacing a road comprising a unit supported for movement along the surface to be covered by means operating on said surface, a material leveling unit embodying a leveling member adapted to act upon material applied to the surface to be covered, means for supporting said leveling member on the second-named unit and adapted to be actuated to move said leveling member to various vertical positions on said second-named unit, means for supporting said second-named unit for movement along the surface to be covered, said means operating along the surface to be covered, means for connecting said units together to permit relative vertical movement thereof, and means for actuating said leveling member supporting means to automatically change the vertical position of said leveling member as the machine moves vertically in passing along over the surface to be covered, said means comprising a control member sup-

ported on the machine for vertical movement relative to the leveling member at a point behind said leveling member and adapted to ride on the surface produced by said leveling member, said lever arm having its forward end pivotally connected to said first-named unit, said lever arm being operatively connected to said leveling member supporting means at a point intermediate the ends of said arm so as to actuate said leveling member supporting means to move said leveling member vertically in an opposite direction whenever the leveling member moves vertically relative to the control member in one direction during movement of the machine along the surface to be covered.

12. A machine for surfacing a road comprising supporting means for supporting the machine for movement along the surface to be covered, a material leveling member adapted to act upon material applied to the surface to be covered, means for supporting said leveling member on the machine and adapted to be actuated to move said leveling member to various vertical positions on the machine, and means for actuating said leveling member supporting means to automatically 25 change the vertical position of said leveling member as the machine moves vertically in passing along over the surface to be covered, said means comprising a control member supported on the machine for vertical movement relative to the leveling member at a point behind said leveling member and adapted to ride on a surface having a predetermined grade line, said control member being carried by the rear end of a lever arm, said lever arm having its forward end pivotally connected to the machine, said lever arm being operatively connected to said leveling member supporting means at a point intermediate the ends of said arm so as to actuate said leveling member supporting means to move said leveling member vertically in an opposite direction whenever the leveling member moves vertically relative to the control member in one direction during movement of the machine along the surface to be covered.

13. A machine for surfacing a road comprising supporting means for supporting the machine for movement along the surface to be covered, a material leveling member adapted to act upon material applied to the surface to be covered, means for supporting said leveling member on the ma-

chine and adapted to be actuated to move said leveling member to various vertical positions on the machine, and means for actuating said leveling member supporting means to automatically change the vertical position of said leveling member as the machine moves vertically in passing along over the surface to be covered, said means comprising a control member supported on the machine for vertical movement relative to the leveling member at a point behind said leveling member and adapted to ride on the surface produced by said leveling member, said control member being carried by the rear end of a lever arm, said lever arm having its forward end pivotally connected to the machine, said lever arm being operatively connected to said leveling member supporting means at a point intermediate the ends of said arm so as to actuate said leveling member supporting means to move said leveling member vertically in an opposite direction whenever the leveling member moves vertically relative to the control member in one direction during movement of the machine along the surface to be covered.

14. A machine for surfacing a road comprising a leveling member adapted to act upon material applied to the surface to be covered, means for supporting said leveling member on the machine and adapted to be actuated to move said leveling member to various vertical positions on the machine, means for supporting said machine for movement along the surface to be covered, and means for actuating said leveling member supporting means to automatically change the vertical position of said leveling member on the machine as the machine moves vertically in passing along over the surface to be covered, said means comprising a control member supported on the machine for vertical movement relative to the leveling member and adapted to ride on a surface having a predetermined grade line, said control member being operatively connected to said leveling member supporting means so as to actuate said leveling member supporting means to move said leveling member vertically in an opposite direction whenever the leveling member moves vertically relative to the control member in one direction during movement of the machine along the surface to be covered.
